(57) **CLAIM**

We claim the ornamental design for a modular couch, as shown and described.

DESCRIPTION

FIG. 1 is a perspective front-left view of a first section of a modular couch showing our new design;

FIG. 2 is a front elevational view of the first section of the modular couch;

FIG. 3 is a perspective front-left view of a second section of the modular couch;

FIG. 4 is a perspective front-left view of a third section of the modular couch;

FIG. 5 is a left side elevational view of the second section of the modular couch, the right side elevational view being the same as the left side elevational view;

FIG. 6 is a perspective front-left view of the modular couch having the first, second, and third sections adjoined laterally, a back and a seat cushions being disposed on each of the first and second sections;

FIG. 7 is a perspective rear-left view of the modular couch of FIG. 6, a back and a seat cushions being disposed on each of the first and second sections;

FIG. 8 is a perspective front-left view of the modular couch having the second section adjoined laterally to the first section and the third section adjoined frontally to the second section;

FIG. 9 is a perspective front-left view of the modular couch of FIG. 8, a back and a seat cushions being disposed on each of the first, second, and third sections;

FIG. 10 is a perspective front-right view of the modular couch of FIG. 8;

FIG. 11 is a perspective front-right view of the modular couch of FIG. 9;

FIG. 12 is a perspective rear-left view of the modular couch of FIG. 8;

FIG. 13 is a perspective rear-left view of the modular couch of FIG. 9;

FIG. 14 is a top plan view of the modular couch of FIG. 8;

FIG. 15 is a top plan view of the modular couch of FIG. 9;

FIG. 16 is a perspective rear-right view of the modular couch of FIG. 9;

FIG. 17 is a perspective bottom view of the modular couch of FIG. 9;

FIG. 18 is a front elevational view of the modular couch having the first and second sections adjoined laterally;

FIG. 19 is a front elevational view of the modular couch of FIG. 18, a back and a seat cushions being disposed on each of the first and second sections;

FIG. 20 is a rear elevational view of the modular couch of FIG. 18;

FIG. 21 is a front elevational view of the modular couch having the third and first sections adjoined laterally, a back and a seat cushions being disposed on the first section, a seat cushion being disposed on the third section, the first section being rotated 90 degrees with respect to the disposition of the first section in FIG. 19;

FIG. 22 is a rear elevational view of the modular couch of FIG. 21; and,

FIG. 23 is a rear elevational view of the modular couch of FIG. 21 without cushions disposed thereon.
